[57] CLAIM

The ornamental design for neckwear, as shown and described.

DESCRIPTION

FIG. 1 is a front elevational view of neckwear showing my new design as broken off for convenience of illustration;

FIG. 2 is a right side elevational view; and
FIG. 3 is a front elevational view of another embodiment of neckwear showing my new design wherein the bottom portion is shortened.

The rear of both embodiments is plain and unornamental, and is obscured and concealed when the neckwear is worn.
